UNITED STATES PATENT OFFICE.

HOWARD D. RANDALL, OF CINCINNATI, OHIO.

FRICTIONAL CONTACT WINDOW GUIDE.

Application filed June 23, 1924. Serial No. 721,641.

REISSUED

To all whom it may concern:

Be it known that I, HOWARD D. RANDALL, a citizen of the United States of America, and a resident of Cincinnati, in the county of Hamilton and State of Ohio, have invented a new and useful Improvement in a Frictional Contact Window Guide, of which the following is a specification.

My invention as embodied in the instant disclosure is concerned with providing a yielding structure for use as a guide, channel or run, in which glass window plates, such as are used in the doors and windows of sedan automobiles, may be retained and reciprocated. It will be readily evident that the invention lends itself to other uses, and that the form of the yielding structure may be modified to adapt same to various other uses.

An object of my invention is to provide a structure which, when developed into a channel for guiding reciprocating plate glass windows and the like, will exert a yielding pressure upon the glass, thereby precluding rattling thereof.

Another object of my invention is to provide a structure for the purpose stated that may be flexed in any direction, whereby to facilitate positioning thereof in the doors of automobile bodies.

Another object of my invention is to provide a structure of the class described that may be economically and expeditiously produced and applied.

Another object of my invention is to provide a structure wherewith a positive spring contact may be effected with the sides of the glass and the like.

These and other objects are attained by the means described herein, and disclosed in the accompanying drawings, in which:

Fig. 1 is a view showing the elements of a device embodying my invention in position preparatory to mounting thereof, one upon the other.

Fig. 2 is an end view of the parts shown in Fig. 1.

Fig. 3 is a perspective view of the parts shown in Figs. 1 and 2, after same has been developed into a channel preparatory to mounting thereof upon a vehicle door or frame.

Fig. 4 is a fragmental perspective view, part in section, showing a structure as dis-

closed in Fig. 3 in position in a door, and 55 operative upon a fragment of a plate glass.

Fig. 5 is an end view of a modified form of device embodying my invention.

Briefly my structure comprises a wire mat or core 12 for which a flexible covering 11 is 60 provided. The core 12 is produced preferably from wire, having desired spring characteristics, and is bent backwardly and forwardly in the manner disclosed in Fig. 1 for providing a substantially flat rectangular 65 wire mat. The wire 10 may be of any suitable cross section and the particular configuration of the various loops developed along the lateral edges of the wire mat may be varied and modified to meet various conditions. The flexible covering 11 is preferably provided on its inner face with an adhesive so that when the wire mat 12 is placed upon the flexible covering 11, and the lateral ends 13 and 14 of the flexible material are bent over the wire mat, the adhesive will serve to bind the opposed portions of the flexible material, where such sections contact through the openings 15 formed interiorly of the loops 16 developed 70 along the lateral edges of the wire mat 12. In Fig. 2, the ends 13 and 14 are shown in dotted lines in their fixed positions relative to the underlying position 17 of the covering material. The structure, after fixa- 75

tion of the ends 13 and 14, is then bent to the desired form, for example to the channel form shown in Figs. 3 and 5, whereupon the channel may be inserted in the run or way 18 that forms part of a vehicle door or the 80 like, and in which the plate glass window 19 or the like is received. It will be readily evident that the flexible material 11 may be reinforced by capping the looped ends 12 of the wire mat prior to the turning inward 85 of the lateral edges 13 and 14 of the flexible material 11. It will be readily evident that the flat structure disclosed in Fig. 2, after the ends 13 and 14 are affixed, may be developed into various flexible forms other 90 than the channel 20, wherefore I do not restrict my invention to the specific form into which such flat structure might be developed.

Although the invention as disclosed here- 95 in comprises spring wire having resilient qualities, it will be readily evident that under some circumstances such qualities might be undesirable, wherefore it is not

intended to restrict the invention to a structure wherein the wire is resilient or yielding.

What I claim is:

- 5 1. As a new article of manufacture a channel comprising a flexible covering, and a resilient mat contained within the covering and comprising a continuous spring wire extending in alternate directions, and having
- 10 its lateral edges disposed at angles to the intermediate portions thereof for providing the side walls of the channel.
- 15 2. A channel structure of U shaped cross section comprising a resilient wire mat and a flexible covering for the mat, the mat comprising a serpentine wire looped along its lateral edges and having its lateral edges turned relative to the intermediate or base portion thereof, whereby the lateral portions
- 20 of the wire mat form part of the arms of the channel and retain the lateral edges of the flexible covering at an angle to the

center portion of the covering, the said lateral edges of the wire mat and flexible covering providing a way between them 25 through which way a sliding member may be moved, the arms of the channel yieldingly resisting movement of such sliding member.

3. A channel structure of U shape cross 30 section comprising a resilient wire mat and a covering for the mat, the mat and covering being relatively fixed, the mat having its lateral edges turned at an angle and overhanging the intermediate portion or 35 base of the structure for providing a way wider at its bottom than at its top and for yieldingly resisting movement of a sliding member through the way.

In testimony whereof, I have hereunto 40 subscribed my name this 20th day of June, 1924.

HOWARD D. RANDALL.
